FIRE EXTINGUISHER

Julius S. Nelson and Paul A. Stover, San Jose,
Calif.

Application August 19, 1932, Serial No. 629,442

10 Claims. (Cl. 169—26)

The present invention relates particularly to that type of fire extinguisher wherein a frangible container of fire extinguishing material is shattered by means rendered operative by heat generated by the fire to be extinguished, reference being made to the application of Julius S. Nelson, Serial No. 603806, filed April 7, 1932.

In a device of the type indicated it is desirable to have the liquid receptacle disposed within a container having an open end through which the liquid may be discharged, and it is one object of the invention to provide means for breaking the receptacle within the container.

It is another object of the invention to provide breaker means that constitutes a single unit that may be quickly and easily positioned in and removed from the container.

It is still another object to provide breaker means that functions as a support for the receptacle in the container.

It is also an object of the invention to provide breaker means of the character indicated that will be economical to manufacture, simple in form and construction, light, strong, durable, and highly efficient in its practical application.

In the drawing:

Figure 1 is a sectional view of a device embodying our invention, partly in elevation and part broken away.

Figure 2 is a section on line 2—2 of Figure 1.

Figure 3 is a sectional view of a device embodying another form of the invention, partly in elevation, and part broken away.

Figure 4 is a section on line 4—4 of Figure 3.

In the embodiment of the invention shown in the Figures 1 and 2, a container is indicated by the reference 1 closed at its top and provided with supporting means at 2, its lower end being open, and having an internal annular groove 3 formed therein as at 3.

At 4 is shown a spreader discharge plate having an upturned side edge as at 5 provided with bosses 6 adapted to engage the groove 3 whereby to securely hold this element in place.

An inverted cup shaped element is shown at 7, this element being of such a diameter that it will slide snugly into the container 1, its edge resting on the upper edge of the spreader 4 when the two parts are in position. In the top 50 of this element are formed symmetrically disposed openings as 8—9 and sockets 10 and 11. In the sockets 10—11 are mounted resilient members 12—13 fitted with heads 14—15. The free ends of these members are provided with tongues 16—17 engaging holes 18—19 in the

ends of a short bar 20, the said bar being formed of two parts connected by a suitable fusible material at 21 and, of course, holding the members under tension.

Disposed within the container or housing, and resting upon the element 7, is a frangible receptacle for fire extinguishing liquid, as 22.

When the bar 20 separates through the fusing of the connecting medium, the resilient members 12—13 are released and throw their heads 14—15 through the openings 8—9 and against the receptacle 22 with sufficient force to shatter the same and permit the liquid therein to flow downwardly through openings 8—9 and thence out through the spreader 4.

In the embodiment shown in Figures 3 and 4, the container 23 is fitted with a distributor 24 upon which rests an inverted cup shaped element 25. The top of element 25 has a central opening formed therein as at 26 through which projects a protuberance 27 on receptacle 28. Struck inwardly from one side of the element 25 are fingers 29, these fingers clasping and holding a resilient member 30 bent back upon itself as at 31 and with its ends secured together by any suitable substance fusible at a given temperature. On the end of the bent-back portion of this member is a head 32. In this embodiment when the hot air fuses the connector at 33 the resilient element throws the head 32 forwardly against the protuberance 27 which is thereby shattered thereby releasing the liquid contents of the receptacle.

It is to be understood, of course, that while we have herein shown and described but two specific embodiments of the invention, changes in form, construction, and method of assembly and operation may be made within the scope of the appended claims.

We claim:

1. The combination of a container having a lower discharge end, liquid distributing means disposed in said end, a breaker device slidably engaging the container and disposed upon and supported by the distributing means a frangible receptacle for fire extinguishing liquid disposed in the container and supported by said breaker device, and said breaker device being constructed and arranged to break the frangible container when subjected to a predetermined temperature, and to pass the released liquid to the distributing means.

2. The combination of a container having an open lower end, liquid distributor means mounted in said end, a frangible receptacle for fire

- extinguishing material disposed in the container, and a breaker device mounted in the container in operative relation to the receptacle, the said device including an apertured plate disposed beneath the receptacle, a pair of resilient hammers mounted on the plate and tending normally to operate through the apertures, and heat releasable means connecting the hammers to normally hold them in an inoperative position. 5
- 10 3. A breaker device of the character described comprising a member adapted to underlie and support a receptacle for fire extinguishing liquid and having oppositely disposed orifices formed therein, a pair of resilient hammers mounted therein and operative through said orifices, and heat releasable means connecting the hammers to normally hold them in an inoperative position. 15
4. In combination, a container having a lower discharge end, a frangible receptacle for fire extinguishing material mounted therein, supporting means for the receptacle disposed within the container and having heat responsive breaker means mounted thereon in operative relation to the receptacle, a liquid distributor mounted in the discharge end of the container to support the supporting means for the receptacle and said supporting means being constructed and arranged to pass the released liquid to the distributing means. 20
- 25 30 5. In combination, a container having a lower discharge end, a frangible receptacle for fire extinguishing material mounted therein, an inverted cup-shaped element mounted in the container to support the receptacle, heat responsive breaker means mounted on said element in operative relation to the receptacle, a distributor member mounted in the discharge end of the container to support said cup-shaped element and said inverted cup-shaped element being constructed and arranged to pass the fire extinguishing material from the receptacle to the distributor. 35
- 40 6. In combination, a container having a lower discharge end, a frangible receptacle for fire extinguishing material mounted therein, an inverted cup-shaped element mounted in the container to support the receptacle, heat responsive breaker means mounted on said element in operative relation to the receptacle, a cup-shaped distributor member slidably inserted in said container to support the inverted cup-shaped element, means for securing the distributor member in the container and said inverted cup-shaped element being constructed and arranged to pass the fire extinguishing material from the receptacle to the distributor member. 45
- 50 7. In combination, a container having a lower discharge end, a frangible receptacle for fire extinguishing material slidably mounted therein, an apertured element slidably mounted in the container to support the receptacle, heat responsive breaker means mounted on said element in operative relation to the receptacle and normally tending to operate through the apertures, and supporting means for the apertured element detachably mounted in the container said means comprising a distributor plate arranged below said element. 55
- 80 8. In combination, a container having a lower discharge end, a frangible receptacle for fire extinguishing material inserted therein, an apertured element inserted in the container to support the receptacle, heat responsive breaker means mounted on said element in operative relation to the receptacle and normally tending to operate through the apertures, and supporting means for the apertured element detachably inserted in the container, said means comprising a distributor plate arranged below said element. 90
- 90 9. A breaker device of the character described comprising a member adapted to underlie a frangible receptacle for fire extinguishing material and having openings therein, hammers mounted thereon and normally tending to operate through the openings, and means connected to the free ends of the hammers to normally hold them in an inoperative position. 95
- 100 10. The structure of claim 9 characterized by said hammers having resilient stems. 105
